UNITED STATES PATENT OFFICE.

CHARLES S. EPPLEY, OF YORK, PENNSYLVANIA, ASSIGNOR TO SELF-ACTING SWITCH CO., A CORPORATION OF DELAWARE.

SWITCH.

1,205,134.

Specification of Letters Patent. Patented Nov. 14, 1916.

Application filed November 24, 1915. Serial No. 63,246.

To all whom it may concern:

Be it known that I, CHARLES S. EPPLEY, a citizen of the United States, residing at York, in the county of York, State of Pennsylvania, have invented a new and useful Switch; and I do hereby declare the following to be a full, clear, and exact description of the invention, such as will enable others skilled in the art to which it appertains to 10 make and use the same.

This invention relates to a switch, and particularly to an improved operating mechanism therefor.

An object of the invention is to provide 15 an improved operating mechanism which is strictly positive in operation. In other words, the different parts or elements of the mechanism coöperate positively.

Another object of the invention is to so 20 arrange and construct the various parts or elements, to insure their full requisite movements or actions, and yet prevent overthrow or movements of the parts.

Another object of the invention is to provide 25 means, adapted to be operated by a member on a car coming in contact with a device in its path, to actuate a mechanism, which includes an eccentric for throwing the switch point to one position, at which time 30 a member of the second means actuates an element, which in turn releases a clutch in the first means, to permit the operating parts of the first means to return to their initial position, and restore the device in the 35 path of a member of the next car.

Another object of the invention is to provide 40 means in the means which includes said eccentric, to prevent the parts of the means with the eccentric from overthrowing, and retrograding.

Another object of the invention is to provide 45 a dust and waterproof casing for the operating mechanism, and one which has its top suitably packed, in order that the casing 50 may be filled practically with lubricant, so that the parts and elements of the mechanism will operate in the oil, to insure lubrication for the parts, and which lubricant may be replenished substantially about every 55 eight, nine or ten months.

Another object of the invention is to provide 60 a tubular casing for the eccentric rod (which has yieldable connections with the switch point) which tubular casing connects

to a second dust and waterproof casing for 55 the yieldable connection, said casing for the yieldable connections being designed to contain lubricant, as well as the tubular casing, to keep the parts lubricated.

Another object of the invention is to provide 60 means to automatically throw the device from the path of the tripping member on the car.

Another object of the invention is to improve 65 and render more efficient and practical the switch operating mechanism described, shown in the drawing, and claimed in the application of C. S. Eppley, filed Feb. 23, 1915, Serial No. 9,913, which has matured into Patent No. 1,165,236, dated 70 21st day of December, 1915.

In practical fields the details of construction may necessitate alterations, falling within the scope of what is claimed.

The invention comprises further features 75 and combination of parts, as hereinafter set forth, shown in the drawings and claimed.

In the drawings: Figure 1 is a view in perspective of the improved switch operating mechanism, as applied to a switch. Fig. 80 2 is a plan view of the casing for the switch operating mechanism, showing the cover of the casing removed to show the operating parts of the mechanism. Fig. 3 is a sectional view on line 3—3 of Fig. 2. Fig. 4 85 is a sectional view on line 4—4 of Fig. 2. Fig. 5 is a sectional view on line 5—5 of Fig. 2. Fig. 6 is a sectional view on line 6—6 of Fig. 4. Fig. 7 is a sectional view on line 7—7 of Fig. 2. Fig. 8 is a plan 90 view of the casing for the connection between the eccentric rod and the switch point, showing the cover of said casing removed to disclose said connections in plan. Fig. 9 is a sectional view on line 9—9 of Fig. 6. 95

Referring more especially to the drawings, 1 and 2 designate the main rails of a track, the main rail 2 merging into the siding or switch rail 3, between which siding or switch rail and the main rail 4 is a switch 100 point 5 pivoted at 6. Adjacent the side of the siding or switch rail is a casing 7 having a cover 8, which is secured at 9 to the casing, there being a suitable packing 10, to insure that the casing will be dust and waterproof. A tubular casing 11 has its flange 13 secured to one side of the casing 7 as shown at 14, the other end of the tubular 105

casing 11 has its flange 15 secured at 16 to the casing 17, which incloses the switch operating mechanism.

The casing 17 is provided with a partition wall 18 which divides the casing into two compartments 19 and 20 and a cover 21 is provided for the casing, there being a suitable packing 22, to prevent dust and water from entering. The cover consists of two sections 23 and 24, which have flanges 25 to overhang the side walls of the casing. The section 23 covers the compartment 20 while the section 24 covers the compartment 19. To make a tight fit with the packing 15 screws 26 are threaded through the cover and into the sides of the casing. The inner face of the side wall 27 of the casing is provided with flanges 28, 29, and 30, and the inner face of the partition 18 is provided 20 with flanges 31, 32 and 33. A one piece bearing member 34 is bolted at 35 to the flanges 28 and 29, and a second one piece bearing 36 is bolted at 37 to the flanges 31 and 32. A shaft 38 is mounted in the bearings 34 and 36 and secured at 39 to one end of the shaft 38 is a collar 40 having a laterally extending arm 41, to which a link 42 is connected at 43 for rocking the shaft 38. The arm 41 and the link 42 operate in 30 the compartment 20. A packing gland consisting of the two parts 44 and 45 for one end of the shaft 38, is mounted in the partition wall 18. A collar 46 is secured on the shaft 38 by the set screw 47, and is provided with a downwardly extending arm 48, to the end of which a spring 49 is connected. The other end of the spring is connected at 50 to an eye of the face of one of the sides of the casing 17. An eccentric 51 is mounted 40 upon the shaft 38, and is made fast to the shaft by the key or feather 52, and to prevent axial movement of the eccentric a collar 53 is secured to the shaft 38 by means of the set screw 54. A gear 55 is mounted 45 loosely upon the shaft 38, and is in mesh with the gear 56 on the shaft 57. The gear 55 has a laterally extending collar 58 provided with clutch teeth 59. A clutch collar 60 is keyed at 61 to rotate with the shaft 38, but is capable of sliding on said shaft, and when moved toward the collar 58, the teeth 62 of the collar 60 coöperate with the teeth 59, so as to cause the gear 55 to rotate with the shaft 38. A spring 64 is interposed 50 between the clutch collar 60 and the collar 53 so as to hold the collar 60 in clutch with the collar 58. The clutch collar 60 is provided with an annular groove 65, one wall of which at diametrically opposite sides of the collar is provided with recesses 66 having cam surfaces 67. The shaft 57 is mounted in the one piece bearings 68 and 69, which are bolted respectively at 70 and 71 to the flanges 32 and 33, and 29 and 30. Made fast 55 upon the shaft 57 by means of the key or

feather 73 is a ratchet disk 74. Rising upwardly from the flange 33 is a lug 75, to which a pawl 76 is pivoted by means of the bolt 77, there being a spring 78 to hold the pawl 76 in engagement with the ratchet to 70 prevent retrograde movement of the ratchet and the shaft 57. Also keyed by the feather 73 on the shaft 57 is a disk 79 having diametrically opposite shoulders 80 and 81, alternately with which the free end 82 of the 75 dog 83 (which is pivoted at 84 in the bifurcated lug 85 of the casing 17) engages, to limit the shaft 57 and the disk 79 when moving in the direction of the arrow *a*. Also made fast to the shaft 57 by the feather or key 73 is an eccentric 87 having an eccentric strap 88, to which the eccentric rod 89 is bolted as at 90. This eccentric rod 89 extends through the tubular casing 11 and into the casing 7. Pivoted at 92 to a lug 93 on 85 the interior of the casing 7 is a bell crank lever 94, the long arm 95 of which has an opening 96 or slot, through which the rod 89 extends, there being coil springs 97 and 98 adjacent the opposite faces of the arm 95. The nuts 99 and 100 hold the springs 97 and 98 so as to bear yieldably against the opposite faces of the arm 95. The short arm 101 is provided with a slot and pin connection 102 with the rod 105, which is 95 mounted in a fluid and dust tight bearing 106 of one side of the casing 7. The rod 105 is in turn connected to the switch point 5. Also keyed by the feather 73 to the shaft 57 is a disk or collar 107 having an annular 100 flange 108, which is provided with diametrically opposite cam portions or surfaces 109 and 110. Pivoted to a post 112, which rises upwardly from the base of the casing 17, is a lever 113, which, upon one side of the 105 pivot, is formed with the arms 114, which arch substantially half way about the clutch collar 60, so that the diametrically opposite pins 115 will play in the annular groove 65 of the clutch collar 60. The other end of the 110 lever 113 is notched as shown at 116 to co-operate with the flange 108 and its diametrically opposite cam surfaces 109 and 110, so that the lever 113 will be oscillated horizontally during the rotation of the shaft 57. 115 The gear 56 is made fast to the shaft 57 by means of a key or feather 117. A slide 118 upon its under face is provided with a dove-tailed rib 119, which is dove-tailed in the groove or guide 120, and in the bottom of the guide 120 a slot 121 is formed, and projecting downwardly from the under face of the section 23 of the cover and upon opposite sides of the slot 121 are cam flanges 122.

Mounted to move vertically in an opening 123 of the slide 118 is a plate or bar 124, which is also mounted in the guide slot 121. Riveted at 125 to the slide and extending downwardly into the compartment 20 is a bracket arm 126, between the arm 127 of 120

which and the bar or plate 124 a coil spring 128 is interposed, so as to hold the bar or plate 124 in its uppermost position, with the opposite ends of the pin 129 against the under surface of the section 43 of the cover. The bifurcated end 130 of the link 42 is pivoted at 131 to the lug 132 of the bracket 126. The bar or plate projects above the slide 118, and is in close position to one side of the main rail 2, so that a member 134 (which may be carried by a car moving in the direction of the arrow *b* in Fig. 1) may contact with the projecting part of the bar or plate 124. Owing to the bar or plate 124 closely but slidably fitting the opening 123, the slide 118 will be moved forwardly, in which case owing to the link connection 42, the shaft 38 will be rocked in the direction of the arrow *c*. Owing to the gear 55 being in clutch with the shaft 38, the shaft 57 will be partially rotated, for instance, substantially one half revolution, by the gear 55 and the gear 56. Just as soon as the shaft 38 starts rotating the eccentric 51 will move so as to lower the dog 83, so that its free end will engage the surface following the shoulder 80, the disk 79 having moved a trifle past the free end of the dog 83, in which case the shaft 57 will rotate through the medium of the gears 55 and 56. While the shafts 38 and 57 are rotated as indicated by the arrows in Fig. 2, the lever 113 will oscillate idly. In other words, the pins 115 will ride the cam surfaces 67 of the diametrically opposite recesses 66, while the notched end 116 will ride from engagement with the cam surface 109 of the flange 108 of the disk or collar 107. It is to be noted that the shaft 38 will make substantially one third revolution to substantially one half revolution of the shaft 57, and therefore the cam surface 110 will reach the notched end 116 of the lever 113, before the diametrically opposite recesses 66 again reach the diametrically opposite pins 115, in which case the clutch collar 60 will be moved toward the collar 53, disengaging the teeth 59 and 62, and owing to the gear 55 being loose upon the shaft 38 the shaft 38 is free to return to its initial position. However, the shaft 38 is rocked against the action of the spring 49. When the shaft 57 is rotating, the eccentric rod 89 is reciprocated in the direction of the arrow *d* in Fig. 2, and also in Fig. 8, in which case the bell crank lever 94 is oscillated upon its pivot, to throw the switch point toward and against the main rail 4 as in Fig. 1, thereby permitting the car to pass on to the siding or switch rail 3. As before stated, every time the switch point is moved in one direction or the other, the shaft 57 makes one-half revolution, and is limited positively to this revolution by the dog 83 being released from its elevating position, so that its end 82 will contact with the shoulder 81 of the disk 79. When the shaft 38 completes its one third revolution, the bar or plate has been moved downwardly by the opposite ends of the pin 129 riding upon the cams 122, so as to withdraw the bar or plate 124 from the path of the member 134. The clutch members 58 and 60 are disengaged at the same time the bar or plate 124 is withdrawn from the path of the member 134, so that by the action of the spring 49, the shaft 38 is returned to its initial position. When the shaft 38 reaches its initial position, the cam 51 will raise the dog 83 sufficiently, so that its free end 82 is offset a little above the shoulder 81, so that when the shafts 38 and 57 are again rotated toward each other, the disk or member 79 will have moved sufficiently, to permit the dog 83 to ride upon the surface of the disk 79 following the shoulder 81. When the shaft 38 is returned to its initial position, the pins 115 will again engage the diametrically opposite recesses 66, in which case the clutch collar or member 60 will again be thrown in clutch with the collar 58. When the shaft is returned to its initial position the slide 118 is also returned. When the shaft 57 is again rotated, the eccentric will be returned to the position shown in Fig. 2, thereby returning the switch point to the position shown in Fig. 8. The shaft 57 rotates in the same direction, but intermittently. When a car is moving in a direction opposite to that indicated by the arrow *b* in Fig. 1, either moving on the main rail, or from the switch rails to the main rails, and the switch point is in contact with the main or switch rail, the flanges of the car wheel will force the switch points against the action of the yieldable connections with the eccentric rod, without jamming the switch operating mechanism, owing to said yieldable connection.

The invention having been set forth, what is claimed as new and useful is:—

1. In combination with a switch including a switch point, an operating mechanism including an intermittently revoluble shaft having an eccentric and rod connection with the switch point, means including a rocking shaft in gear with said first shaft, a device adapted to be actuated by a member on the car and being connected to the rock shaft for rocking the same one third of a revolution to substantially one half of a revolution of the first shaft, means connecting the two shafts and means whereby as the rocking shaft completes its one third revolution, the rocking shaft is thrown out of gear with the revoluble shaft, and means for returning the rocking shaft to its initial position.
2. In combination with a switch including

- a switch point, an operating mechanism including an intermittently revoluble shaft having an eccentric and rod connection with the switch point, means including a rocking 5 shaft in gear with said first shaft, a device adapted to be actuated by a member on the car and being connected to the rocking shaft for rocking the same one third of a revolution to substantially one half of a revolution 10 of the first shaft, means connecting the two shafts and means whereby as the rocking shaft completes its one third revolution, the rocking shaft is thrown out of gear with the revoluble shaft, and means for returning 15 the rocking shaft to its initial position, and means for withdrawing the device from the path of the member on the car to permit the rocking shaft to return to its initial position.
- 20 3. In combination, a switch having a switch point, an intermittently revoluble shaft having connections with the point, a rocking shaft, a gear loosely mounted thereon and having gear connections with the 25 first shaft, a clutching member keyed to the rocking shaft and having clutch connections with the loose gear, a device adapted to be actuated by a member on a car and being connected to the rocking shaft, connections 30 between the intermittent revoluble shaft and the clutch member, whereby upon the completion of a half revolution of the intermittent shaft, the clutch member is oscillated to throw the rocking shaft out of 35 clutch with its gear, to permit the rocking shaft to turn to its initial position.
- 40 4. In combination, a switch having a switch point, a dust and water proof casing, an intermittently revoluble shaft mounted in the casing and having connections with the point, a rocking shaft mounted in the casing, a gear loose upon the rocking shaft and having gear connections with the first 45 shaft, a clutch member keyed to the rocking shaft and having clutch connections with the loose gear, a device adapted to be actuated by a member on a car and being connected to the rocking shaft, connections between the intermittent revoluble shaft and the clutch member to throw the rocking shaft out of clutch with its gear upon the completion of a half revolution of the intermittently revoluble shaft, and means to return the rocking shaft and said device to their initial positions.
- 50 5. In combination, a switch having a switch point, a casing, an intermittently revoluble shaft mounted in the casing and having connections with the point, a rocking shaft mounted in the casing, a gear loose upon the rocking shaft and having gear connections with the first shaft, a clutch member keyed to the rocking shaft and having clutch connections with the loose gear, a device adapted to be actuated by a member
- on a car and being connected to the rocking shaft, connections between the intermittently revoluble shaft and the clutch member to throw the rocking shaft out of clutch with its gear upon the completion of a half revolution of the intermittently revoluble shaft, and means to return the rocking shaft and said device to their initial positions, and means to prevent retrogression of the intermittently revoluble shaft. 75
6. In combination, a switch having a switch point, a casing, an intermittently revoluble shaft mounted in the casing and having connections with the point, a rocking shaft mounted in the casing, a gear loose upon the rocking shaft and having gear connections with the first shaft, a clutch member keyed to the rocking shaft and having clutch connections with the loose gear, a device adapted to be actuated by a member on a car and being connected to the rocking shaft, connections between the intermittently revoluble shaft and the clutch member to throw the rocking shaft out of clutch with its gear upon the completion of a half revolution of the intermittently revoluble shaft, and means to return the rocking shaft and said device to their initial positions, and means to prevent retrogression of the intermittently revoluble shaft. 80
7. In combination, a switch having a switch point, a casing, an operating mechanism in said casing, and comprising a pair of shafts, one being rockable a substantially third revolution to substantially one half intermittent revolution of the other shaft, the intermittently revoluble shaft having an eccentric and rod connection with the switch point, a gear loose on the rocking shaft and in gear with the other shaft, a clutch keyed to the rocking shaft and in clutch with its gear, said clutch including diametrically opposite recesses, a cam on the intermittent shaft, a device to be actuated by a member on a car and being connected to the rocking shaft, and means coöperating between the cam and the recesses of the clutch member to throw the clutch upon the completion of half revolution of the intermittent shaft to allow the rocking shaft to return to its initial position. 90
8. In combination, a switch having a switch point, a casing, an operating mechanism in said casing, and comprising a pair of shafts, one being rockable a substantially third revolution to substantially one half intermittent revolution of the other shaft, the intermittently revoluble shaft having an eccentric and rod connection with the switch point, a gear loose on the rockable shaft and in gear with the other shaft, a clutch keyed to the rocking shaft and in clutch with its gear, said clutch including diametrically op- 100

posite recesses, a cam on the intermittent shaft, a device to be actuated by a member on a car and being connected to the rocking shaft, and means coöperating between the cam and the recesses of the clutch member to throw the clutch upon the completion of a half revolution of the intermittent shaft to allow the rocking shaft to return to its initial position, and means for returning the 10 rocking shaft to its initial position.

9. In combination, a switch having a switch point, a casing, an operating mechanism in said casing, and comprising a pair of shafts, one being rockable a substantially 15 third revolution to substantially one half intermittent revolution of the other shaft, the intermittently revoluble shaft having an eccentric and rod connection with the switch point, a gear loose on the rocking shaft and 20 in gear with the other shaft, a clutch keyed to the rocking shaft and in clutch with its gear, said clutch including diametrically opposite recesses, a cam on the intermittent shaft, a device to be actuated by a member 25 on a car and being connected to the rocking shaft, and means coöperating between the cam and the recesses of the clutch member to throw the clutch upon the completion of a half revolution of the intermittent shaft 30 to allow the rocking shaft to return to its initial position, and means for returning the rocking shaft to its initial position, and means to withdraw the device from the path of the member on the car to allow the rocking 35 shaft to return to its initial position.

10. In combination, a switch having a switch point, a casing, an operating mechanism in said casing, and comprising a pair of shafts, one being rockable a substantially 40 third revolution to substantially one half intermittent revolution of the other shaft, the intermittently revoluble shaft having an eccentric and rod connection with the switch point, a gear loose on the rocking shaft and 45 in gear with the other shaft, a clutch keyed to the rocking shaft and in clutch with the gear, said clutch including diametrically opposite recesses, a cam on the intermittent shaft, a device to be actuated by a member 50 on a car and being connected to the rocking shaft, and means coöperating between the cam and the recesses of the clutch member to throw the clutch upon the completion of a half revolution of the intermittent shaft 55 to allow the rocking shaft to return to its initial position, and means for returning the rocking shaft to its initial position, means to prevent retrogression of the intermittent shaft, and means to prevent an overthrow 60 of the intermittent shaft.

11. In combination, a switch having a switch point, a casing, an intermittently revoluble shaft mounted in said casing having connections with the switch point, a de-

vice actuated by a member on a car having 65 connections with said shaft, said connections including a pair of gears, and means actuated by the intermittent shaft upon the completion of a half revolution of said shaft to temporarily sever said connections to permit the device to be withdrawn from the path of said member. 70

12. In combination, a switch having a switch point, a casing, an intermittently revoluble shaft mounted in said casing, 75 means connecting said shaft with the switch point, a device actuated by a member on a car having connections with said shaft, and means actuated by the intermittent shaft upon the completion of a half revolution of said shaft to temporarily render said first 80 mentioned means incapable of further rotating said shaft, means to withdraw the device from the path of said member, and means to restore said first means to their 85 initial position.

13. In combination, a switch having a switch point, a casing, an intermittently revoluble shaft mounted in said casing, means connecting said shaft with the switch 90 point, a device actuated by a member on a car having connections with said shaft, and means actuated by the intermittent shaft upon the completion of a half revolution of said shaft to temporarily render said first 95 mentioned means incapable of further rotating said shaft, means to withdraw the device from the path of said member, and means to restore said first mentioned means to their initial position, and means to prevent 100 backward movement of said shaft.

14. In combination, a switch having a switch point, a casing, an intermittently revoluble shaft mounted in said casing, means connecting said shaft with the switch 105 point, a device actuated by a member on a car having connections with said shaft, and means actuated by the intermittent shaft upon the completion of a half revolution of said shaft to temporarily render said first 110 mentioned means incapable of further rotating said shaft, means to withdraw the device from the path of said member, and means to restore said first means to their initial positions, and means to prevent backward 115 movement of said shaft, and means to prevent an overthrow of said shaft.

15. In combination, a switch having a switch point, a casing, a revoluble shaft mounted in said casing having an eccentric 120 and rod connection with the switch point, a device to be actuated by a member on a car, means including a pair of intermeshing gears connecting said device and said shaft to operate the shaft a half revolution, a 125 clutch in said means, a cam on said shaft, and means actuated by said cam to operate the clutch upon the completion of the half

revolution of the shaft, to render the first means incapable of operating the shaft more than a half turn.

16. In combination, a switch having a switch point, a casing, a revolute shaft mounted in said casing having an eccentric and rod connection with the switch point, a clutch having one of its members geared to said shaft, a device to be actuated by a member on a car, means connecting said device and the other member of said clutch to operate the shaft a half revolution, a cam on said shaft, and means actuated by said cam to operate the clutch upon the completion of the half revolution of the shaft, to render the first means incapable of operating the shaft more than a half turn, and means to return the first means to its initial position when rendered incapable.
17. In combination, a switch having a switch point, a casing, a revolute shaft mounted in said casing having an eccentric and rod connection with the switch point, a clutch having one of its members geared to said shaft, a device to be actuated by a member on a car, means connecting said device and the other member of said clutch, an element on said shaft, means actuated by said element to open the clutch when the shaft will have made a substantially half revolution, to render the first means incapable of operating the shaft further, and means to return the first means to its initial position.
18. In combination, a switch having a switch point, a casing, a revolute shaft mounted in said casing having an eccentric and rod connection with the switch point, a clutch connected to said shaft, a device to be actuated by a member on a car, means connecting said device and said clutch, an element on said shaft, means actuated by said element to open the clutch when the shaft will have made a substantially half revolution, to render the first means incapable of operating the shaft further, and means to return the first means to its initial position, and means to withdraw the device from the path of said member on the car.
19. In combination, a switch having a switch point, a casing, a revolute shaft mounted in said casing having an eccentric and rod connection with the switch point, a clutch comprising two members, gears connecting one of the members of the clutch and said shaft, a device to be actuated by a member on a car, means connecting said device and the other member of the clutch, an element on said shaft, means actuated by said element to separate the members of the clutch when the shaft will have made a substantially half revolution, to render the first means incapable of operating the shaft further, and means to return the first means to its initial position, and means to withdraw the device from the path of said member on the car.
20. In combination, a switch having a switch point, a casing, a revolute shaft mounted in said casing having an eccentric and rod connection with the switch point, a clutch connected to said shaft, a device to be actuated by a member on a car, means connecting said device and said clutch, an element on said shaft, means actuated by said element to open the clutch when the shaft will have made a substantially half revolution, to render the first means incapable of operating the shaft further, and means to return the first means to its initial position, and means to withdraw the device from the path of said member on the car, and means to prevent an overthrow of said shaft.

21. In combination, a switch having a switch point, a casing, a revolute shaft mounted in said casing having an eccentric and rod connection with the switch point, a clutch connected to said shaft, a device to be actuated by a member on a car, means connecting said device and said clutch, an element on said shaft, means actuated by said element to open the clutch when the shaft will have made a substantially half revolution, to render the first means incapable of operating the shaft further, and means to return the first means to its initial position, and means to withdraw the device from the path of said member on the car, and means to prevent an overthrow of said shaft.

22. In combination, a switch having a switch point, a casing, a revolute shaft mounted in said casing having an eccentric and rod connection with the switch point, a clutch comprising two members, gears connecting one of the members of the clutch and said shaft, a device to be actuated by a member on a car, means including a pair of intermeshing gears connecting said device and the other members of the clutch, an element on said shaft, means actuated by said elements to separate the members of the clutch when the shaft will have made a substantially half revolution, to render the first means incapable of operating the shaft further, and means to return the first means to its initial position, and means to withdraw the device from the path of said member on the car, a second element on said shaft, a cam operable with the first means, and means normally supported by the cam and allowed to gravitate to coöperate with the second element to prevent an overthrow of the shaft.

23. In combination, a switch having a switch point, a casing, a revolute shaft mounted in said casing having an eccentric and rod connection with the switch point, a clutch comprising two members, gears connecting one of the members of the clutch and said shaft, a device to be actuated by a member on a car, means including a pair of intermeshing gears connecting said device and the other members of the clutch, an element on said shaft, means actuated by said elements to separate the members of the clutch when the shaft will have made a substantially half revolution, to render the first means incapable of operating the shaft further, and means to return the first means to its initial position, and means to withdraw the device from the path of said member on the car, and means to prevent retrogression of said shaft, a second element on said shaft, a cam operable with the first means, and a second device normally supported by the cam and allowed to gravitate as the cam rotates to coöperate with the second element to prevent an overthrow of the shaft.

24. In combination, a switch having a

switch point, a casing, a revoluble shaft mounted in said casing having an eccentric and rod connection with the switch point, a clutch connected to said shaft, a device to be actuated by a member on a car, means connecting said device and said clutch, a device to be actuated by a member on a car, means connecting said device and said clutch, an element on said shaft, and means actuated by said element to open the clutch when the shaft will have made a substantially half revolution, to render the first means incapable of operating the shaft further.

24. In combination, a switch having a switch point, a casing, a revoluble shaft mounted in said casing having an eccentric and rod connection with the switch point, a clutch comprising two members, gears connecting one of the members of the clutch

and said shaft, a device to be actuated by a member on a car, means connecting said device and the other members of the clutch, 20 an element on said shaft, and means actuated by said element to separate the members of the clutch when the shaft will have made a substantially half revolution, to render the first means incapable of further operating the shaft. 25

In testimony whereof I have signed my name to this specification in the presence of two subscribing witnesses.

CHARLES S. EPPLEY.
